UNITED STATES PATENT OFFICE.

SAMUEL B. FREDERICK, OF DETROIT, MICHIGAN.

DESIGN FOR A RUBBER HEEL.

56,000.

Specification for Design.

Patented Aug. 10, 1920.

Application filed January 5, 1920. Serial No. 349,616. Term of patent 14 years.

To all whom it may concern:

Be it known that I, SAMUEL B. FREDERICK, a citizen of the United States of America, residing at Detroit, county of Wayne, and State of Michigan, have invented a new, original, and ornamental Design for Rubber Heels, of which the following is a specification, reference being had to the accompanying drawing, forming part thereof.

In the drawing,—

Figure 1 is a perspective of my rubber heel.

Fig. 2 is an elevation on the face thereof.

Fig. 3 is a cross-section.

a represents the rubber heel which is tapered from the rear at *b* to the front as at *c* and is provided with a series of arcuate grooves *d*, *d* and is slightly concave on the face in front of the front groove. These grooves from rear to front of the heel form arcs of successive circles of increasing diameter and are undercut, as indicated at *e*.

I claim:

The ornamental design for a rubber heel as shown and described.

SAMUEL B. FREDERICK.
